UNITED STATES PATENT OFFICE.

VALENTINO L. BIANCHI AND GEORGE A. HOLZBERG, OF SAN FRANCISCO, CALIFORNIA;
SAID HOLZBERG ASSIGNOR TO SAID BIANCHI.

FILE HOLDER.

Application filed November 22, 1926. Serial No. 150,052.

This invention relates to file holding and flexing mechanisms or devices and has for its primary object the provision of means for supporting a flexible file so that it can be effectively adjusted to adapt itself to the shape of the object to be operated upon.

Another object of the invention is to provide means of this character which will be positive and quick of action and of a design whereby it can be manually actuated with accuracy where the file will truly conform with the shape of the surface operated upon.

A further object of the invention is to provide means of this character which will be reliable for the purpose intended, light of weight and inexpensive of manufacture.

Another object of the invention is to provide means whereby pressure may be brought to bear evenly upon the file while in action.

Another object of the invention is to provide means for effecting quick attachment of a file to or removal of same from the hold as the occasion demands.

With the above and other objects in view which will appear as the nature of the invention is better understood, the same consists in the improved construction and novel arrangements of parts which will hereinafter be fully described and particularly pointed out in the claims.

In the accompanying drawings has been illustrated the preferred form of the invention, it being, however, understood that no limitations are necessarily made to the precise structural details therein exhibited, but that changes, alterations and modifications within the scope of the claims may be resorted to when desired.

The figure is a view in side elevation with parts in section, showing the file in full lines when occupying a plane position, and in dotted lines when flexed to respective positions. In carrying the invention into practice use is made of companion grips 5 and 6 which are shaped to adapt themselves to the two hands of an operator for convenience of operation and for the purpose of permitting equal pressure to be applied thereto when the file is moved against its work. The two grips 5 and 6 are connected together by a turn-buckle 7 whose rod sections 8 and 9 are pivotally joined at 10 to said grips so that the latter are free to tilt relatively. In order to accomplish this end satisfactorily the outer extremities of the rod sections 8 and 9 are

seated in compensating cavities 11 formed in the inner faces of said grips. The rod sections are respectively provided with right and left hand threads which are accommodated in the correspondingly threaded bores 12 and 13 in the nut 14 of said turn-buckle. The turn-buckle thus characterizes a means which is adjustable longitudinally or in its length, so that the grips 5 and 6 can be tilted to occupy positions that determine a given flexure of a plane.

The grips 5 and 6 are employed in conjunction with a flexible, normally flat file 15 of the reversible or two-faced type. The respective ends of the file are formed with apertures 16 through which screws 17 are passed. These screws find engagement in threaded bores 18 formed in the grips axially thereof. The lower faces of the grips are flat and relatively broad, so as to come into effective or full contact with the surfaces of the file against which they are presented. The grip 6 is formed at its base with a depending lug 19 which serves as an abutment for an adjacent transverse edge of the file blade, thus serving at a stress point to relieve the screws 17 of any material strain.

As shown in full lines, the grips 5 and 6 are substantially in parallelism, at which time the file 15 is in a horizontal flat plane. When the grips are adjusted to a second position designated at B in dotted lines, the file assumes a position of flexure where its working or exposed surface is arcuate or concave. In this position the effective working surface of the file is calculated to adapt itself to a surface of corresponding curvature. When adjusted to a third position indicated by the dotted lines C, the effective working surface of the file is relatively curved, so that it is convexed longitudinally. Many intermediate positions of adjustment of the file can be had almost instantly, so that it can be made to quickly and accurately come into true conformation with the surface to be filed.

It is, of course, understood that in using the device the file is actuated against the surface being acted upon as is common or within the customary skill of the user, but it is important to bear in mind that positioning the grips 5 and 6 in their relative order as previously set forth herein enables the work of filing to be carried on with dispatch and thoroughness with an equal expenditure of pressure of the file against its work.

While we have shown only the preferred form of the invention, it should be understood that various changes or modifications may be made within the scope of the claims hereto attached without departing from the spirit of the invention.

We claim:

1. A device of the class described comprising a pair of spaced tilting grips, a turning buckle operatively connected with said grips to tilt same and to hold the grips in fixed positions of tilted adjustment, and means for securing the respective ends of a flexible file to said grip.
- 15 2. A flat blade of the character described having operating elements extending from

one face thereof in spaced relation so as to allow the blade to be bent into a curve by operation of the members and an adjustable member connecting the operating elements 20 and adapted to bend the blade.

3. A device of the character described comprising a flat blade having operating elements extending from one face thereof in spaced relation and an adjustable member connect- 25 ing the two elements, the adjustable member being spaced from the blade to allow the latter to be bent in either direction by manipulation of the said member.

VALENTINO L. BIANCHI.
GEORGE A. HOLSBERG.
